FIGURE 1 is a side elevational view of a container for pulverulent material or the like showing my new design;

FIGURE 2 is a top plan view thereof;

FIGURE 3 is a bottom plan view thereof; and

FIGURE 4 is an enlarged fragmentary cross-sectional view thereof taken along the reference line 4—4 of FIGURE 1;

The sides of the container for pulverulent material or the like not illustrated are the same as that shown. The dominant features of my design reside in the portions shown in full lines.

I claim:

The ornamental design for a container for pulverulent material or the like, substantially as shown and described.
